ABSTRACT OF THE DISCLOSURE

This invention concerns novel furanone derivatives of the formula

wherein

R₁ is lower alkyl or cycloalkyl, and
R₂ is hydrogen, fluorine, chlorine, bromine, lower alkyl or lower alkoxy,

useful as analgesic and central nervous system depressant agents.

The present invention relates to furanone derivatives. The invention provides compounds of formula I,

wherein

R₁ is alkyl of 1 to 6 carbon atoms or cycloalkyl, and
R₂ is hydrogen, halogen of atomic number from 9 to 35, lower alkyl or lower alkoxy.

Further, in accordance with the invention, a compound of formula I may be obtained by a process comprising reacting a compound of formula II,

wherein R₂ is as defined above,

with a compound of formula III,

wherein R₁ is as defined above.

When R₁ in the compounds of formula I is alkyl, this preferably contains 1 to 4 carbon atoms and especially signifies isopropyl. When R₁ is cycloalkyl, this preferably contains 3 to 8, especially 5 or 6 carbon atoms. When R₂ is lower alkyl or alkoxy, these groups preferably contain 1 to 3 carbon atoms and especially signify methyl or methoxy, respectively. When R₂ is halogen, this preferably is fluorine or chlorine.

The process of the invention is preferably effected in an inert solvent, e.g. an aromatic hydrocarbon such as benzene, toluene or xylene. The reaction temperature is preferably from about 100 to 180° C., preferably 120 to 160° C. Conveniently an excess of an isocyanate of formula III is used. The reaction is preferably effected in a sealed vessel, e.g., an autoclave, especially when low-boiling compounds of formula III or low-boiling solvents are used.

In so far as the production of starting materials is not particularly described these compounds are known or may be produced and purified in accordance with known processes, or in a manner analogous to the processes described herein or to known processes.

The compounds of formula I may be isolated from the reaction mixture and purified in known manner. The free base forms of the compounds of formula I may be converted into acid addition salt forms in conventional manner and *vice versa*.

The compounds of formula I have not been described in the literature.

The compounds of formula I are useful because they possess pharmacological activity in animals. In particular, the compounds of formula I are useful as analgesic agents, as indicated in standard tests, for example, the hot plate test in mice on p.o. administration of 10 to 50 mg./kg. animal body weight of the compounds, and, as further indicated, by an inhibition of the phenylbenzoquinone syndrome in mice on p.o. administration of 10 to 50 mg./kg. animal body weight of the compounds.

For the above mentioned use the dosage will, of course, vary depending on the compound employed, mode of administration and therapy desired. However, in general, satisfactory results are obtained when administered at a daily dosage of from 1 mg. to about 50 mg. per kg. animal body weight, conveniently given in divided doses 2 to 4 times a day or in sustained release form. For the larger mammals, the total daily dosage is in the range from about 50 to about 500 mg., and dosage forms suitable for oral administration comprise from about 12 mg. to about 250 mg. of the compounds admixed with a solid or liquid pharmaceutical carrier or diluent.

3-[1-(4-p-fluorophenyl-4-oxobutyl) - 4 - isopropylcarbamoyloxy-4-piperidyl]dihydro-2(3H)-furanone has particularly interesting properties.

The compounds of formula I are furthermore useful as central nervous system depressants, as indicated in standard tests, for example, the climbing test and the rotating rod test on i.p. administration of 1 to 10 mg./kg. animal body weight, of the compounds, and, as further indicated, by a depression of the rectal temperature in mice on i.p. administration of from 15 to 30 mg./kg. animal body weight of the compounds.

For this use the dosage will, of course, vary depending on the compound employed, mode of administration and treatment desired. However, in general, satisfactory results are obtained when administered at a daily dosage of from about 1 mg. to about 30 mg. per kg. animal body weight, conveniently given in divided doses 2 to 4 times a day or in sustained release form. For the larger mammals, the total daily dosage is in the range from about 50 to about 500 mg., and dosage forms suitable for oral administration comprise from about 12 mg. to about 250 mg. of the compounds admixed with a solid or liquid pharmaceutical carrier or diluent.

The compounds of formula I may be administered in pharmaceutically acceptable acid addition salt form. Such acid addition salt forms exhibit the same order of activity as the free base forms and are readily prepared in conventional manner. Representative acid addition salt forms include organic acid salt forms such as the hydrogen maleate, fumarate, tartrate and methane sulphonate and

mineral acid salt forms such as the hydrochloride, hydrobromide and sulphate. A pharmaceutical composition may comprise a compound of formula I, in free base form or in pharmaceutically acceptable acid addition salt form, in association with a pharmaceutical carrier or diluent. Such compositions may be prepared by conventional techniques to be in the form of, for example, capsules, tablets, suppositories, suspensions or solutions, for enteral or parenteral administration. Aside from the usual pharmaceutical diluents or carriers, e.g. water, alcohols, natural or hardened oils and waxes, these pharmaceutical compositions may contain suitable preserving, stabilizing, wetting, solubilizing, sweetening, flavouring or colouring agents.

In the following non-limitative Examples all temperatures are indicated in degrees Centigrade.

EXAMPLE 1: Dihydro-3-[4-isopropylcarbamoyloxy-1-(4-oxo-4-phenylbutyl)-4-piperidyl]-2(3H)-furanone

A solution of 10 g. of dihydro-3-[4-hydroxy-1-(4-oxo-4-phenylbutyl)-4-piperidyl]-2(3H)-furanone and 11.4 cc. of isopropyl isocyanate in 100 cc. of benzene is heated to 120° for 36 hours in an autoclave. The contents of the autoclave are evaporated to dryness, the resulting title compound is dissolved in ethanol and converted into the hydrochloride form by the addition of hydrochloric acid in ethanol. The crude product is crystallized from methanol for purposes of purification. The hydrochloride form of the title compound has a M.P. of 216-218° (decomp.).

Analysis:

Calculated: C, 61.0; N, 6.2; H, 7.3%.
Found: C, 61.3; N, 6.1; H, 7.5%.

The following compounds of formula I may also be produced in a manner analogous to that described in Example 1, by reacting the corresponding compounds of formula II with isopropyl isocyanate:dihydro-3-[4-isopropylcarbamoyloxy-1-(4-oxo-*o*-tolylbutyl)-4-piperidyl]-2(3H)-furanone,

Analysis:

Calculated: C, 67.0; N, 6.5; H, 8.0%.
Found: C, 66.7; N, 6.3; H, 8.2%.

3-[1-(4-*m*-chlorophenyl - 4 - oxobutyl)-4-isopropylcarbamoyloxy-4-piperidyl]dihydro-2(3H)-furanone,

Analysis:

Calculated: C, 61.3; N, 6.2; H, 6.9%.
Found: C, 61.5; N, 6.4; H, 6.8%.

dihydro-3-[4 - isopropylcarbamoyloxy - 1-(4-*p*-methoxyphenyl-4-oxobutyl)-4-piperidyl]-2(3H)-furanone,

Analysis:

Calculated: C, 64.6; N, 6.3; H, 7.7%.
Found: C, 64.3; N, 6.5; H, 7.9%.

Example 2: 3-[4-ethylcarbamoyloxy-1-(4-oxo-4-phenylbutyl)-4-piperidyl]-dihydro-2(3H)-furanone

12 g. of dihydro-3-[4-hydroxy-1-(4-oxo-4-phenylbutyl)-4-piperidyl]-2(3H)-furanone and 30 cc. of ethyl isocyanate are heated in 120 cc. of benzene at 140° in an autoclave for 48 hours, and the reaction mixture is worked up as described in Example 1. The hydrochloride form of the title compound has a M.P. of 205-208° (decomp.) from methanol.

EXAMPLE 3: 3-[4-cyclohexylcarbamoyloxy-1-(4-oxo-4-phenylbutyl)-4-piperidyl]dihydro-2(3H)-furanone

12 g. of dihydro-3-[4-hydroxy-1-(4-oxo-4-phenylbutyl)-4-piperidyl]-2(3H)-furanone and 54.6 g. of cyclohexyl isocyanate are heated in 120 cc. of benzene at 140° in an autoclave for 48 hours, and the reaction mixture is worked up as described in Example 1. The hydrochloride form of the title compound has a M.P. of 207-208° (decomp.) from methanol.

EXAMPLE 4: 3-[1-(4-*p*-fluorophenyl-4-oxobutyl)-4-isopropylcarbamoyloxy - 4 - piperidyl]-dihydro-2(3H)-furanone

7.5 g. of dihydro-3-[4-hydroxy-1-(4-*p*-fluorophenyl-4-oxobutyl)-4-piperidyl]-2(3H)-furanone and 11.5 cc. of isopropyl isocyanate are heated in 400 cc. of benzene at 160° in an autoclave for 21 hours, and the reaction mixture is worked up as described in Example 1. The hydrochloride form of the title compound has a M.P. of 220-221.5° (decomp.) from methanol.

EXAMPLE 5: Dihydro-3-[4-methylcarbamoyloxy-1-(4-oxo-4-phenylbutyl)-4-piperidyl]-2(3H)-furanone

8.5 g. of dihydro-3-[4-hydroxy-1-(4-oxo-4-phenylbutyl)-4-piperidyl]-2(3H)-furanone and 7.3 g. of methyl isocyanate are heated in 100 cc. of benzene at 120° in an autoclave for 15 hours, and the crude title compound is converted into its hydrogen maleate form. M.P. 181-182° from methanol.

EXAMPLE 6: 3-[1-(4-*p*-fluorophenyl-4-oxobutyl)-4-N-isopropylcarbamoyloxy - 4 - piperidyl]-dihydro-2(3H)-furanone

9 g. of dihydro-3-[4-hydroxy-1-(4-*p*-fluorophenyl-4-oxobutyl)-4-piperidyl]-2(3H)-furanone and 8.6 g. of propyl isocyanate are heated in 100 cc. of benzene at 120° in an autoclave for 20 hours, and the reaction mixture is worked up as described in Example 1. The hydrochloride form of the title compound is recrystallized once from acetone and twice from methanol and has a M.P. of 215-216° (decomp.).

What is claimed is:

1. A compound of the formula

wherein

R₁ is alkyl of 1 to 6 carbon atoms or cycloalkyl of 3 to 8 carbon atoms, and

R₂ is hydrogen, halogen of atomic number from 9 to 35, alkyl of 1 to 3 carbon atoms or alkoxy of 1 to 3 carbon atoms,

or a pharmaceutically acceptable acid addition salt thereof.

2. The compound of Claim 1, which is dihydro-3-[4-isopropylcarbamoyloxy - 1 - (4-oxo-4-phenylbutyl)-4-piperidyl]-2(3H)-furanone.

3. The compound of Claim 1, which is dihydro-3-[4-isopropylcarbamoyloxy - 1 - (4 - oxo-4-*o*-tolylbutyl)-4-piperidyl]-2(3H)-furanone.

4. The compound of Claim 1, which is 3-[1-(4-*m*-chlorophenyl - 4 - oxobutyl)-4-isopropylcarbamoyloxy-4-piperidyl]dihydro-2(3H)-furanone.

5. The compound of Claim 1, which is dihydro-3-[4-isopropylcarbamoyloxy - 1 - (4-*p*-methoxy-phenyl-4-oxobutyl)-4-piperidyl]-2(3H)-furanone.

6. The compound of Claim 1, which is 3-[4-ethylcarbamoyloxy-1-(4-oxo-4-phenylbutyl)-4-piperidyl]-dihydro-2(3H)-furanone.

7. The compound of Claim 1, which is 3-[4-cyclohexylcarbamoyloxy-1-(4-oxo-4-phenylbutyl)-4 - piperidyl]-dihydro-2(3H)-furanone.

8. The compound of Claim 1, which is 3-[1-(4-*p*-fluorophenyl-4-oxobutyl) - 4 - isopropylcarbamoyloxy-4-piperidyl]-dihydro-2(3H)-furanone.

9. The compound of Claim 1, which is dihydro-3-[4-methylcarbamoyloxy-1-(4-oxo - 4-phenylbutyl)-4-piperidyl]-2(3H)-furanone.

10. The compound of Claim 1, which is 3-[1-(4-p-fluorophenyl-4-oxobutyl)-4 - N-propylcarbamoyloxy-4-piperidyl]-dihydro-2(3H)-furanone.
